ARTHUR PENTECOST, OF EAST ORANGE, NEW JERSEY, ASSIGNOR TO THE ADDER MACHINE COMPANY, OF WILKES-BARRE, PENNSYLVANIA, A CORPORATION OF PENNSYLVANIA.

CALCULATING-MACHINE.

1,238,809.

Specification of Letters Patent.

Patented Sept. 4, 1917.

Application filed July 8, 1916. Serial No. 108,187.

To all whom it may concern:

Be it known that I, ARTHUR PENTECOST, a subject of the King of England, residing at East Orange, Essex county, New Jersey, have invented new and useful Improvements 5 in Calculating-Machines, of which the following is a specification.

The invention relates more particularly to piece or item counting mechanisms for calculating machines, wherein a portion of the regular counters of such machines are utilized for counting the number of pieces, items or amounts set up on the keyboard.

It has been customary to provide means to 15 effect the automatic step by step rotation of one or more of the regular counters of a calculating machine, to register and accumulate thereon an amount corresponding to the number of checks, cars, bales or other items, 20 pieces or articles, the amounts, weights, or values of which are accumulated on other of the regular counters reserved for such calculations.

In some cases, the carrying mechanism has 25 been disabled between the counter of highest denomination reserved for the accumulation of amounts, weights, or values, and the counter of lowest denomination on which are accumulated the number of pieces or items, 30 but the permanent disabling of the carry prevents the machine from accumulating amounts to its full capacity, as a normal machine.

Many of the devices applied to prior machines, for effecting piece counting, are 35 driven from the main shaft of the machine, and will operate to count or accumulate a succession of "ones" on blank or idle strokes. This type of item counters are really stroke 40 counters, and open the way for an inaccurate count of the items.

Other devices employed to count items on one or more of the regular counters of a calculating machine, which are free from 45 the above objection, will effect a count of "one" on a non-print operation of the machine, thereby confusing the operator, because the total number of items listed will be less than the total number registered on 50 the item counting section of the accumulator.

It is highly desirable that the counting of an item take place only when such item is entered on the keyboard and the machine

operated, and one object of the invention is 55 to provide a novel, and accurate keyboard-controlled means to effect the counting of items, or the like on a part of the regular accumulating mechanism of the machine.

Another object is the provision of readily 60 accessible means to control the operation of an item counting mechanism, which means can be adjusted at will, to effect or prevent item counting, the machine being adapted for normal operation to its full capacity 65 when the item counting mechanism is ineffective.

A further object is to provide a means to 70 effect item counting which becomes operative only when an amount set up on the keyboard is listed or printed.

A still further object is the provision of 75 novel means to prevent the count of "one" when taking a total or sub total.

Further objects are the provision of a 75 simple, durable, and easily controlled device of this nature, which may be readily applied to machines now in use, and comprises but few parts not liable to get out of order.

The foregoing and other objects and ad- 80 vantages will be more fully pointed out hereinafter and particularly set forth in the claims.

In the accompanying drawings, Figure 1 85 is a side view, partly in section, of the well known Wales calculating machine, equipped with one embodiment of my invention, in normal position;

Fig. 2 is a detail view, in side elevation, 90 of the accumulating and printing sections viewed from the left, showing the mechanism set for operation, the hammers being fired;

Fig. 3 is a fragmentary top plan view, 95 showing one means to manually control the item counting device for operation, conditional upon the setting up of an item on the keyboard, and the operation of the machine;

Fig. 4 is a perspective detail of the rock- 100 ing yoke or frame and trip arm, disassembled;

Fig. 5 is a detail right hand side view, 105 showing the locking mechanism effective to prevent the operation of the item counting device, the hammers being fired, and

Fig. 6 is a similar view, showing the total key-controlled locking mechanism in operative position, the hammers being fired.

Although I have shown the invention applied to a Wales machine, it is understood that the device is not restricted in its use thereto, but may be readily adapted to other machines.

Attention is also directed to U. S. patents to Wales, #794,205, July 11, 1905; #797,032, August 15, 1905; McFarland, #842,232, January 29, 1907; McFarland and Wales, #880,157, February 25, 1908; Bickford, #1,066,700, July 8, 1913; and Wilgus, #1,133,596, March 30, 1915, for a more complete explanation of the Wales machine, the description of which hereinafter will be made as brief as possible, consistent with a clear understanding of the present invention.

Calculating machines of the Wales type comprise a keyboard mechanism, an accumulator section, and a printer section supported between side frames 967 and inclosed within a removable casing 1065 (a fragment only of which is shown in Figs. 1 and 2).

The keys 117 of the keyboard are arranged in denominational rows, there being generally as many counters 490 in the accumulator section as there are rows of keys, and a similar number of typecarriers 514 (Fig. 2) in the printing section, with their respective groups of printing members, including hammers 510.

Depressing numeral keys 117 (Fig. 1) in the rows or banks of the keyboard, projects stops 115 into the paths of counter-driving members 310, each of which is pivoted on a pair of front and rear supporting arms 312, and 311, journaled on the cross shaft 300 and cross rod 301, respectively.

A restraining and restoring bar 205 contacts the front supporting arms 312 to normally hold the drive members 310 in re-tired position, against the action of their drive springs 383 which connect the respective rear supporting arms 311 and the restraining bar 205.

Turning the main drive shaft 200 journaled in the side frames 967, rocks a crank 210 engaging a cam-slotted arm 220 fast with the restraining and restoring bar 205 to withdraw the latter and tension the driving springs 383, to advance the racks or drive members 310 until arrested by the key-controlled stops 115 or by displaceable detents 221 in those banks wherein no keys have been depressed.

The counters 490 are each equipped with pinions 435 and normally remain disengaged from their drive members 310, but as the main drive shaft approaches the end of its forward stroke, it trips well known counter-supporting means (not shown) to effect the engagement of the pinions 435 with the drive members. (See Fig. 5.)

The counter supports are tripped and reset through the operation of a swinging rod

303 (Fig. 1) hung from the cross shaft 300 by means of radius bars 323 journaled thereon.

Links 214 connect the swinging rod 303 with cranks 212 on the main shaft 200 to 70 oscillate the rod.

The counter drive members 310, on their advance, rock extensions 311^a of their rear supporting arms 311 to raise the typecarriers 514, connected to the extensions by links 75 515, and position the proper types 561 at the printing line.

A group of printing members for each typecarrier, includes a printing hammer 510 (Figs. 1 and 2) journaled on a cross shaft 80 500, and driven at the proper time by a spring 580 against a firing pin 562^a in line with the positioned type to effect the imprint of the type on the work sheet.

A hammer pawl 511 normally retains the 85 printing hammer 510 in cocked position, and a universal latch 518 restrains the entire series of hammers against operation. Cross-over tails 511^a on the hammer pawls 511 enable a pawl to the left to release all pawls 90 to the right thereof in the customary manner to print ciphers to the right of a significant digit.

A simple split and normal device is provided to interrupt cipher printing to the 95 right, of well known construction, and for this reason is not illustrated.

As the extensions 311^a rock upwardly, they release trip bars 513 which displace the hammer pawls 511 of denominations corresponding to the banks of the keyboard where-in keys have been depressed, to enable the printing of significant digits.

The swinging rod 303, on the forward stroke of the main drive shaft, operates 105 through a link 526 to rock a bell crank 524 pivoted on a cross rod 508, and connected by a second link 527 to another bell crank 525 fast on a cross shaft 500, to rock the cross shaft 500. Arms 519 on the shaft support a hammer resetting bail 509. Rocking the shaft 500 on the forward stroke of the main drive shaft, withdraws the hammer resetting bail 509 beyond the travel of the hammers 510.

At the same time, a link 525^a (Fig. 1) which connects the bell crank 525 to an arm 513^a on a shaft 502, rocks the shaft 502 which carries arms 512 supporting a tensioning bail 505, (Fig. 2) to which the hammer drive 120 springs 580 are secured, to store power in the springs.

A connecting bar 528 pivoted at 538 to the bell crank 525, is slotted to accommodate a stud 555 projecting from an arm 517 to 125 which the universal hammer latch 518 is secured, so that after the individual hammer pawls 511 are released, the hammer resetting bail 509 withdrawn, and the hammer springs 580 tensioned, the universal latch 130

518 is lifted to free the hammers to the action of their springs and effect an imprint of the types 561 as the main shaft approaches the end of its forward stroke.

5 Main restoring springs (not shown) effect the return stroke of the main drive shaft 200, during which the restraining and restoring bail 205 retires the counter driving members 310 to normal position. The drive 10 members, on their retirement, turn their counters 490 to register or accumulate thereon the amount corresponding to the values of the depressed keys.

As the shaft 200 approaches its normal 15 idle position, and after the amounts have been registered, the returning swinging rod 303, by familiar mechanism (not shown) lifts the counters 490 bodily to disengage the pinions 435 from their drive members 310.

20 Also, the swinging rod 303, during its restoration to normal position, presses the hammer resetting bail 509 against the discharged hammers 510 to return them to cocked position where they are held by the 25 individual hammer pawls 511, released for action by the retirement of the counter drive members 310 and trip bars 513. The tensioning bail 505 is also shifted to relieve the hammer drive springs 580 of a part of their 30 tension, and the universal latch 518 is returned to effective position.

Carrying mechanisms are provided for the counters to transfer the "tens" from counters of lower denomination to those of 35 next higher denomination.

Such carrying mechanisms each include a rocker 610 journaled on a cross rod 600 and equipped with a carrying dog 610^a adapted to engage a toothed ratchet 410 on the corresponding counter 490 to drive the counter 40 one step forwardly.

A spring 680 drives the rocker 610 and its carrying pawl 610^a against the ratchet 410, and a trigger 612 having a step 635 in the 45 path of one arm 610^b of the rocker, normally retains the rocker and pawl in cocked or set position.

The triggers are journaled on a cross rod 600^a extending between the side frames of 50 the machine, and are held in place by springs 681.

Each counter carries a cam finger 411 so arranged that as the counter turns from its "9" to its "0" position, the cam finger will 55 wipe past and trip the trigger 612 to free the rocker 610 and its pawl 610^a to the action of the spring 680 which drives the pawl into mesh with the ratchet 410 on the counter of next highest denomination, to turn the 60 latter one step.

Means to delay the carrying operation, and reset the carrying mechanism is shown in Fig. 1, but not described in detail, as the principle of this mechanism is fully disclosed in the prior patents referred to.

It is sufficient to state that the tripped carrying mechanisms are reset at the end of each forward stroke in readiness to be tripped during the return stroke of the main drive shaft, should a carrying operation be 70 necessary.

The foregoing mechanisms are all well known in the art and constitute a part of the present invention only in so far as they are combined with the novel features hereinafter disclosed.

It will be recalled that the setting up of amounts on the keyboard controls the operation of the printer section and the groups of printing members. To utilize one or more 80 of the regular counters 490 of the machine on which to effect an accumulation of the number of items set up on the keyboard, I have contrived a means operable from the printer section to trip the carrying 85 mechanism of a selected counter each time an amount is entered on the keyboard and printed.

To this end, I journal a tripping arm or member 1 on a cross shaft 40^a mounted in 90 the side frames 967 of the machine. Preferably, the arm forms a part of a substantially U-shaped rocking yoke or frame 2 journaled on the cross shaft, the arm extending forwardly to a point above and adjacent the trigger 612 of the selected carrying mechanism, and having a yielding tappet or finger 3 slidably mounted by a headed pin and slot connection 4, at its outer end. A spring 5 tends to hold the free end 95 of the finger 3 normally projected beyond the free end of the arm 1, the outer end of the finger having an inclined face 6 adapted to wipe idly over the trigger when the arm swings downwardly to its set position, 100 (Fig. 2).

The trip arm 1 is normally held in idle position (Fig. 1) by a link or actuator 8, against the tension of a setting spring 7 attached at one end to the arm. A slot 9 110 in the actuator link fits over a pin 10 projecting from a rearwardly extending crank 11, preferably forming an integral part of the trip arm 1 or of the rocking frame 2 on which the arm is mounted, and a restoring 115 spring 12 conveniently secured at its ends to the pin 10 and to a pin 13 on the link, flexibly connects the crank and link, the latter being supported and guided in its rectilinear travel by a stud 14 projecting from a 120 fixed plate 420 through a guide slot 15 in the link. Collars 16 mounted on the stud on opposite sides of the link prevent lateral play thereof.

A stud or projection 18 located preferably 125 on one of the printing hammers 510, contacts a toe 17 on the actuator link to draw the latter downwardly and maintain the link at one end of its travel, when the hammer is in cocked or set position. Such pro- 130

jection is preferably mounted on the units hammer which operates when any amount is printed, and the rocking frame spans the distance between the upper end of the actuator link adjacent the hammer of lowest denomination, and the tripping arm adjacent a carrying mechanism corresponding with a counter of much higher denominational value, the frame serving as a connector between the actuating link and tripping arm.

18 The tripping arm 1 is rocked downwardly to its set position (Fig. 2) by the setting spring 7 attached to the arm on one side of its fulcrum, but the shifting of the actuator link 8 by the contact of the projection 18 with the toe 17 on the link, tensions the superior restoring spring 12 connected to the tripping arm 1 on the opposite side of its fulcrum, which restoring spring, therefore, overcomes the setting spring and maintains the trip arm in its elevated or normally idle position. A check, as an arm 20, connected to the trip arm 1 or to the rocking frame 2, contacts a stationary part of the machine, as 25 the cross rod 402, to arrest the trip arm in cocked position (Fig. 1) against the tension of the restoring spring.

When no keys are depressed, the idle stroking of the main drive shaft 200 will 30 have no effect on the mechanism for effecting item counting, the racks or drive members 310 being arrested by the rack detents 221 before they have advanced sufficiently to enable the trip bars 513 to release the individual hammer pawls 511. Consequently, 35 the units hammer 510 remains cocked and the projection 18 carried thereby, retains the link actuator 8 in retracted position.

Turning the main drive shaft when an 40 amount is set up on the keyboard, releases the printing hammers 510, as heretofore explained, and the units hammer, as it turns on its shaft 500 in firing, withdraws its projection 18 from the path of the toe 17 of the 45 actuating link 8, thereby freeing the link to the action of the tensioned restoring spring 12 which immediately contacts, and draws the link upwardly, guided by the stud 14, the collars 16, and the pin 10. The relaxation 50 of the spring 12 also enables the tensioned setting spring 7 to rock the frame 2 and tripping arm 1 from normal position (Fig. 1) to set position (Fig. 2) during which, the cam face 6 of the finger or tappet 3 contacts the trigger 612 and yields 55 rearwardly, to wipe idly over the trigger without displacing the latter, because at that time the carry-resetting mechanism is substantially inoperative, and the displacement 60 of the trigger would have no effect on the counter.

The arm 1 may be arrested on its setting stroke by contact with the hub of the pinion 435.

65 The hammer cocking bail 509 restores the

hammers on the return stroke of the main shaft, during which operation, the projection 18 on the units hammer contacts the advanced toe 17 of the actuating link 8 and returns the link to normal position.

The link, as it retires, tensions the restoring spring 12, which overcomes the setting spring 7 and swings the rocking frame 2 and tripping arm 1 upwardly until the finger or tappet 3 contacts the trigger 612. The finger does not yield on the return travel of the arm 1, and the resistance offered by the trigger 612 and its spring 681 to the action of the restoring spring 12 is sufficient to arrest the arm in contact with the trigger until the hammer projection 18 has nearly returned the actuator link to normal position, storing more energy in the restoring spring. Just as the actuator link is drawn to its normal position, the outer end wall of the slot 9 in the link contacts the pin 10 on the rocking frame 2 and positively rocks the arm 1 upwardly. This positive action causes the arm 1 to wipe past and trip the trigger 612, whereupon the restoring spring 12 is freed to return the rocking frame to idle position.

The trigger, when tripped, releases the carrying rocker 610 to the action of its drive spring 680, which tilts the rocker, and forces the carrying pawl 610^a thereon against the ratchet 410 of the adjacent counter 490 to turn the latter one step and thus effect the item count.

The check arm 20 by its contact with the 100 stationary rod 402 operates to arrest the frame 2 against the tension remaining in the restoring spring 12 after raising the frame, which tension is sufficient to overcome the tension stored in the setting spring 95 by the restoration of the frame to its normal position.

From the foregoing, it will be seen that the automatic counting of items will not 110 occur unless an amount has been set up on the keyboard to permit the release of at least one hammer.

The split or interruption of cipher printing to the right in the printing section, is effected at a point between the hammer corresponding with the counter of lowest denomination reserved for the accumulation of the item count, and the hammer of similar denomination to the counter of highest value in the section reserved for the accumulation of amounts.

It is desirable that a total of the item count registered on the counters to the left of the split, be printed when a total of the amounts or items accumulated to the right of the split is taken, but as the printing of the total of the amounts involves the operation of the units printing hammer 510, means is provided to disable the item counting mechanism during such total taking, to 130

preserve the accuracy of the count and permit the counters appropriated to register such count to clear, when desired.

Depression of the total key 327 (Fig. 1) 5 rocks a lever 317, one arm of which is connected to a slide member 320 guided on studs 358 in the side frame 967, to advance the slide. A shoulder 320^a (Figs. 1 and 6) on the slide contacts a pin 454 on an arm 10 412^a projecting from an alinement bar 412 journaled on a cross rod 403 in the side frames. The slide rocks the alinement bar 412 to interpose abutments 412^b thereon into the paths of the cam fingers 411 on the respective counters to arrest the latter in their zero positions in the customary manner, as shown in Fig. 6.

The upper edge of the alinement bar lies in front of the crank 11 on the rocking 20 frame 2 and carries a keeper 21 normally out of the path of a lug 22 on the crank. When the alinement bar 412 shifts to effective position, however, the keeper 21 swings over the lug 22 to lock the rocking frame 25 and trip arm in cocked position against operation, until the alinement bar returns to normal idle position, and thus prevents the tripping of the carry and the consequent item count when taking totals or sub-totals. 30 The total of the number of items registered on the counters appropriated to the item count will be printed on the same line with the total of the amounts accumulated on the section to the right of the split, the 35 split mechanism preventing the printing of ciphers between the units digit of the total of the number of items, and the digit of highest value in the total of the amounts.

In order to lock out the automatic means 40 which effects a count of the items set up on the keyboard, so that the machine may be used as a normal machine to accumulate items or amounts to its capacity, I provide a manually controlled device which locks 45 the trip arm 1 in cocked position against the action of the setting spring 7. Such lock may be of any convenient form, but in the present instance, it comprises a foot 23 carried by a stub shaft 24, preferably journaled in a plate 25 mounted over an aperture 26 in the casing 1065 of the machine, above the rocking frame 2. A spring 27 coiled about the stub shaft 24 between the foot 23 and the under face of the plate 25, 55 operates to frictionally hold the foot in adjusted position. Turning a thumb piece 28 on the upper end of the shaft projecting above the plate, swings the foot 23 over the check arm 20 to prevent the latter from rising, (Fig. 5) or shifts the foot away from the check arm to enable the frame and trip arm to rock to set position.

The foot carries an abutment 29 (Figs. 2, 5 and 6) adapted to contact the check arm 20 60 in case the locking mechanism is operated

while the check arm is out of its normal position, to thus prevent the effective operation of the locking mechanism. Otherwise, the foot could be interposed between the check arm and its arresting rod 402 to prevent the return of the frame and trip arm to normal cocked position. 70

Stops 30 (Fig. 3) on the plate 25 contacted by a pointer 31 on the shaft 24, arrest the travel of the foot 23 in either direction, 75 and the plate may bear the words "On" and "Off" or other suitable designations adjacent the respective stops to indicate to the operator the position of the locking mechanism. 80

When the locking mechanism is in effective position, the operation of the machine, with an amount set up on the keyboard, will effect the release by the units hammer, of the actuator link 8, which is drawn upwardly by the contraction of the restoring spring 12 until arrested by the contact of the lower end wall of the slot 9 in the link with the pin 10 on the rocking frame 2. The foot 23 prevents the operation of the rocking frame under the influence of the setting spring 7. 90

Recocking the hammers 510 causes the units hammer to restore the link 8 to normal position. 95

Changes may be made in the form and arrangement of the several parts set forth without departing from the spirit and scope of this invention.

What I claim as new, is:— 100

1. The combination in a calculating machine, including a series of counters; and a printing mechanism; of means controlled from the printing mechanism to effect a step by step rotation of one of the counters at 105 each printing operation, for item counting.

2. The combination in a calculating machine, including a series of denominational counters; and groups of printing members corresponding with the denominational counters; of means controlled by the group of printing members of a predetermined denomination to effect a step by step actuation of one of the counters at each operation of the denominational group, for item counting. 110

3. The combination in a calculating machine, with a keyboard; a series of counters, carrying mechanisms therefor; and a series of groups of printing members corresponding with the counters, and controlled from the keyboard; of a trip mechanism to release one of the carrying mechanisms to register a count of items on one of the counters; and means controlled by one of the groups of printing members to effect the operation of the trip mechanism. 120

4. The combination in a calculating machine, with a keyboard; a series of counters; carrying mechanisms therefor; and a printer 130

section, including a series of groups of printing members corresponding with the counters, and controlled from the keyboard; of means to automatically trip one of the carrying mechanisms only, to thereby effect item counting on a selected one of the regular counters, during a printing operation.

5. The combination in a calculating machine, with a keyboard; a series of counters; carrying mechanisms therefor; and a printer section, including a series of groups of printing members corresponding with the counters, and controlled from the keyboard; of means to automatically trip one of the carrying mechanisms during a printing operation only to thereby effect a count on a part of the regular accumulating section, of the number of items printed; and means to disable the carry-tripping mechanism.

10 6. In a calculating machine, the combination with a keyboard; a series of counters; carrying mechanisms therefor; and a printer section, of a printer-controlled means to utilize one or more of the counters for item counting, comprising a trip member to release one of the carrying mechanisms; and an actuator driven from the printer section and connected to the trip member.

15 7. In a calculating machine, the combination with a keyboard; a series of counters; carrying mechanisms therefor; and a printer section; of a printer-controlled means to utilize one or more of the counters for item counting, comprising a trip member to release one of the carrying mechanisms; an actuator driven from the printer section and flexibly connected to the trip member; and means to render the trip member effective or ineffective at will.

20 8. In a calculating machine, the combination with a keyboard; a series of counters; drive members, and carrying mechanisms for the counters; and a printing mechanism, including hammers; of means to utilize one or more of the counters as an automatic item counter, comprising a rocking frame; a trip arm extending from the frame to a point adjacent one of the carrying mechanisms and having a yielding finger thereon; means to rock the arm and finger in one direction past the carrying mechanism; an actuator having a toe normally contacted by one of the printing hammers; and a spring which connects the actuator and rocking frame, to maintain the latter at one limit of its travel against the tension of the means which rocks the trip arm past the carrying mechanism.

25 9. In a calculating machine, the combination with a keyboard; a series of counters; drive members, and carrying mechanisms for the counters; and a printing mechanism, including hammers; of means to utilize one or more of the counters as an automatic item counter, comprising a rocking frame; a trip arm extending from the frame to a point

adjacent one of the carrying mechanisms; means to rock the arm in one direction past the carrying mechanism; an actuator having a toe normally contacted by one of the printing hammers; a spring which connects the actuator and rocking frame, to maintain the latter at one limit of its travel against the tension of the means which rocks the trip arm past the carrying mechanism; and a manually-operable means to render the trip arm effective or ineffective at will.

30 10. In a calculating machine, the combination with a series of counters; carrying mechanisms therefor; a keyboard; and printing mechanism, including hammers, controlled from the keyboard; of means to utilize a portion of the counters for the automatic counting of items, comprising a shiftable member operable to trip one of the carrying mechanisms upon each printing operation; and total key-controlled means effective to lock the shiftable member out of operation when taking a total or clearing the machine.

35 11. In a calculating machine, the combination with a series of counters; carrying mechanisms therefor; a keyboard; and printing mechanism, including hammers, controlled from the keyboard; of means to utilize a portion of the counters for the automatic counting of items, comprising a shiftable member operable to trip one of the carrying mechanisms upon each printing operation; a manually-operable device to render the shiftable member effective or ineffective; and total key-controlled means effective to lock the shiftable member out of operation when taking a total or clearing the machine.

40 12. In a calculating machine, the combination with a series of counters; carrying mechanisms therefor; a keyboard; and printing mechanism, including hammers, controlled from the keyboard; of means to utilize a portion of the counters for the automatic counting of items, comprising a shiftable member to trip one of the carrying mechanisms upon each printing operation; a manually-operable device comprising a rotatable shaft having a bearing in the machine; a foot on the shaft adapted to engage and disengage the item counter; and a spring encircling the shaft between the foot and the bearing and engaging the bearing to hold the shaft in any of its set positions.

45 13. In a calculating machine, the combination with a series of counters; carrying mechanisms therefor; a keyboard; and printing mechanism, including hammers controlled from the keyboard; of means to utilize a portion of the counters for the automatic counting of items, comprising a shiftable member to trip one of the carrying mechanisms upon a printing operation; a manually-operable device to render the

- shiftable member effective or ineffective; and a stop on the device adapted to contact the shiftable member when the latter is in operation to lock the manually-operable device, out of operation at that time. 5

14. In a calculating machine, the combination with a series of counters; carrying mechanisms therefor; a keyboard; and printing mechanism, including hammers controlled from the keyboard; of means to utilize a portion of the counters for the automatic counting of items, comprising a shiftable member to trip one of the carrying mechanisms upon a printing operation; 10 total key mechanism, including an abutment member adapted to be shifted into and out of effective position, to arrest the counters in their zero positions; and a keeper on the abutment member to lock the trip member 15 out of operation when the abutment member is in effective position. 20

15. In a calculating machine, the combination with a series of counters; carrying mechanisms therefor; a keyboard; and printing mechanism, including hammers controlled from the keyboard; of means to utilize a portion of the counters for the automatic counting of items, comprising a shiftable member to trip one of the carrying 25 mechanisms upon a printing operation; total key mechanism, including an abutment member adapted to be shifted into and out of effective position, to arrest the counters in their zero positions; a lug connected with 30 the trip arm; and a keeper on the abutment member, to engage the lug and restrain the trip arm against operation when taking a total or clearing the machine. 35

16. The combination in a calculating machine, with a keyboard; a series of counters controlled thereby; carrying mechanisms for the counters; and a printer section, including printing hammers; of means to utilize a portion of the counters as an item counter, 40 comprising an arm operable upon one of the carrying mechanisms; setting means to rock the arm in one direction; and a restoring device, comprising an actuator link having loose connections, respectively, with the arm 45 and with one of the printing hammers; and a restoring spring to connect the link and arm to restore the latter to, and hold it in its normal position against the action of the setting means. 50

17. The combination in a calculating machine, with a keyboard; a series of counters controlled thereby; carrying mechanisms for the counters; and a printer section, including printing hammers; of means to utilize a portion of the counters as an item counter, 55 comprising an arm operable upon one of the carrying mechanisms; setting means to rock the arm in one direction; a restoring device, comprising an actuator link having loose connections respectively, with the arm 60 and with one of the printing hammers; and a restoring spring to connect the link and arm to restore the latter to, and hold it in its normal position against the action of the setting means; a check device to arrest the trip arm in such position; and a locking member adjustable relatively to the check device to control the operativeness of the trip arm. 65

18. The combination in a calculating machine, with a keyboard; a series of counters controlled thereby; carrying mechanisms for the counters; and a printer section, including printing hammers; of means to utilize a portion of the counters as an item counter, 70 comprising an arm operable upon one of the carrying mechanisms; setting means to rock the arm in one direction; a restoring device, comprising an actuator link having loose connections respectively, with the arm and with one of the printing hammers; and a restoring spring to connect the link and arm to restore the latter to, and hold it in its normal position against the action of the setting means; and total key-controlled means to lock the trip arm out of operation. 75

19. The combination in a calculating machine, with a keyboard; a series of counters controlled thereby; carrying mechanisms for the counters; and a printer section, including printing hammers; of means to utilize a portion of the counters as an item counter, 80 comprising an arm operable upon one of the carrying mechanisms; setting means to rock the arm in one direction; a restoring device, comprising an actuator link having loose connections respectively, with the arm and with one of the printing hammers; and a restoring spring to connect the link and arm to restore the latter to, and hold it in its normal position against the action of the setting means; and separate, independent means to lock the trip arm out of operation. 85

20. The combination in a calculating machine, with a keyboard; a series of counters controlled thereby; carrying mechanisms for the counters; and a printer section, including printing hammers; of means to utilize a portion of the counters as an item counter, 90 comprising an arm operable upon one of the carrying mechanisms; setting means to rock the arm in one direction; a restoring device, comprising an actuator link having loose connections respectively, with the arm and with one of the printing hammers; and a restoring spring to connect the link and arm to restore the latter to, and hold it in its normal position against the action of the setting means; and a check device to arrest the trip arm in such position; and a locking member adjustable relatively to the check device to control the operativeness of the trip arm. 95

21. The combination in a calculating machine, with a keyboard; a series of counters controlled thereby; carrying mechanisms for 100

the counters; and a printer section, including printing hammers; of means to utilize a portion of the counters as an item counter, comprising an arm operable upon one of the carrying mechanisms; setting means to rock the arm in one direction; a restoring device, comprising an actuator link having loose connections, respectively, with the arm and with one of the printing hammers; and a restoring spring to connect the link and arm to restore the latter to, and hold it in its normal position against the action of the setting means; a check device to arrest the trip arm in such position; a locking member adjustable relatively to the check device to control the operativeness of the trip arm; friction means to retain the locking member where adjusted; means to arrest the member at either end of its travel; and means on the locking member to contact the check when the latter is out of normal position to prevent the shift of the locking member to its effective position.

22. The combination in a calculating machine, with a keyboard; a series of counters controlled thereby; carrying mechanisms for the counters; and a printer section, including printing hammers; of means to utilize a portion of the counters as an item counter, comprising a rocking frame having a trip arm to release one of the carrying mechanisms for operation; a setting spring to rock the arm in one direction; a restraining and restoring means for the arm, including an actuator link having a pin and slot connection with the frame; a restoring spring between the link and frame; a toe on the link; and means on one of the hammers to contact the toe and shift the link to one end of its travel to tension the restoring spring and return the trip arm to normal position, against the tension of the setting spring.

23. The combination in a calculating machine, with a keyboard; a series of counters controlled thereby; carrying mechanisms for the counters; and a printer section, including printing hammers; of means to utilize a portion of the counters as an item counter, comprising a rocking frame having a trip arm to release one of carrying mechanisms for operation; a setting spring to

rock the arm in one direction; a restraining and restoring means for the arm, including an actuator link having a pin and slot connection with the frame; a restoring spring between the link and frame; a toe on the link; means on one of the hammers to contact the toe and shift the link to one end of its travel to tension the restoring spring and return the trip arm to normal position, against the tension of the setting spring; and means to check the trip arm in such position.

24. The combination in a calculating machine, with a keyboard; a series of counters controlled thereby; carrying mechanisms for the counters; and a printer section, including printing hammers; of means to utilize a portion of the counters as an item counter, comprising a rocking frame having a trip arm to release one of the carrying mechanisms for operation; a setting spring to rock the arm in one direction; a restraining and restoring means for the arm, including an actuator link having a pin and slot connection with the frame; a restoring spring between the link and frame; a toe on the link; means on one of the hammers to contact the toe and shift the link to one end of its travel to tension the restoring spring and return the trip arm to normal position, against the tension of the setting spring; and adjustable means to retain the trip arm against operation when the hammer is released for printing.

25. The combination in a calculating machine with a keyboard; a series of counters controlled thereby; carrying mechanisms for the counters; and a printer section; of means to utilize a portion of the counters for a count of items, comprising a trip arm operable upon one of the carrying mechanisms; setting means to rock the arm in one direction; a restraining and restoring member to return the arm to normal position, including an actuator link having a loose connection with the arm; a spring to connect the link and arm; and means operated from the printer section to shift the link to one of its positions to tension the restoring spring and overcome the setting means.

ARTHUR PENTECOST.
